CARD PUNCHING MACHINE

Charles O. Wellman, Binghamton, N. Y., assignor to International Business Machines Corporation, New York, N. Y., a corporation of New York

Application October 11, 1934, Serial No. 747,890

14 Claims. (Cl. 164—113)

The present invention is directed to improvements in card punching machines.

In card punching machines it is common practice to provide skip bars for causing certain fields of the cards to be skipped when punching is not desired in such fields. Mechanisms for performing such functions are well known in the art.

Bars of a type known as a "high bar" have usually been provided with suitable means in the first card column position which will cause the carriage to be skipped from such position to a column of another field for numeral punching thereon. It is frequently desirable to have nevertheless, certain cards punched in the first card column position and the present machine provides a simplified structure for preventing the effective action of the skipping mechanism and thus causing the carriage to be retained in the first column position. By the selection of either of two distinct manual means the skip mechanism will be effective or not, dependent upon the manual means selected to return the carriage.

The main object of the present invention is to provide a selective means for causing the skipping mechanism to be effective upon the first card column position of the carriage, or not, as is desired by the operator.

A still further object is the provision of two distinct manual means for selecting the desired operation.

A still further object of the invention is to cause by one of the manual means used for returning the carriage the skipping of the carriage to the first selected field, when it is returned to the first card column position.

Various other objects and advantages of the invention will be obvious from the following particular description of one form of mechanism embodying the invention and from an inspection of the accompanying drawings; and the invention also constitutes certain novel features of construction and combination of parts hereinafter set forth and claimed.

In the drawings:—

Fig. 1 is a top plan view of the complete punching machine which is of a type well known in the art.

Fig. 2 is a side elevation of the central portion of the machine.

Fig. 3 is a detail of a connection between the carriage and the carriage returning mechanism.

Fig. 4 is a plan view of the skip lifter operating mechanism and the manual means provided to control its operation.

Fig. 5 is a view in side elevation of some of the parts shown in Fig. 4.

Fig. 6 is an elevational view taken on the line 6—6 of Fig. 4.

Fig. 7 is a perspective view with some of the parts separated to more clearly show the construction of the skip bar, the skip lifter and the correlated skip lifter retractor mechanism.

As more fully described in the patent to F. L. Lee, et al., No. 1,772,186, dated August 5, 1930 the machine is provided with a handle 2 (Fig. 1), having a normal position at the right hand end of the machine and being mounted for leftward movement along the side of the machine. Whenever the handle 2 is moved to the left it is arranged to shift a rack 3 in the same direction and by means of a picker 4 carried by rack 3 a statistical card is withdrawn from the bottom of a pack in a magazine 5 and advanced to be operated on by a punching mechanism 1.

An escapement rack 6 is provided with teeth 6a (Fig. 2) at its lower side to mesh with a gear 7 and the rack 3 meshes with a gear 8, (Fig. 3) both gears being mounted on a cross shaft 9. The escapement rack 6 carries a pusher 10 (Fig. 2) and a guide 11 which convey the card step-by-step past the punching mechanism 1.

Due to the gear connection 7, 8, the movement of the handle 2 and picker 4 to the left is accompanied by a movement to the right of pusher 10 and this action will deliver a card from the magazine 5 to first column punching position; after which pusher 10 will further advance it step-by-step to pass the punching mechanism. A one-way clutch generally designated 12 in Fig. 3 permits the independent return of the rack bar 3, picker 4, and handle 2 to the right to normal position. The rack 3 meshes with a gear 13 (Fig. 3) secured to a shaft 14 and to said shaft there is connected one end of a coil spring mounted in a spring barrel not shown herein but shown in detail in Fig. 30 in the aforesaid Patent No. 1,772,186. The one way clutch 12 permits the coil spring to return handle 2 and parts movable therewith independent of any movement of the carriage carrying pusher 10 and guide 11.

Escapement mechanism

As more fully explained in the Patents Nos. 1,772,186 and 1,914,263 the depression of any punch key 16 (Fig. 2) is adapted to select and to cause depression of a related interposer 17 which will rock a bail 18 and a shaft 19 connected thereto to render the escapement mechanism 35

effective and the escapement rack 6 and the card carriage will advance one tooth to permit punching in the next column of the card.

Shaft 19 (Fig. 5) has secured at one end oppositely extending arms 20 and 21 of which 20 is provided with a laterally extending pin 22 for engagement with an enlarged opening 23 in a stepping dog 24 which is loosely pivoted on the rod 18. The opposite arm 21 is provided with a pin 25 extending in a slot formed in the locking dog 26 between its pivot and its engaging end. When rod 19 is rocked the arm 20 will through pin 22 lift the stepping dog 24 out of one of the notches in the escapement rack 6 and at the same time arm 21 will depress locking dog 26 into a notch between the rack teeth. At this time a spring 27a advances the loosely pivoted dog 24 a short distance but sufficient to permit this dog to move above the top of the next tooth when the locking dog is again raised. The stepping dog 24, due to the movement of rack 6, will ride down the next tooth until it strikes the end thereof and the carriage is arrested. The usual spring drum (not shown) is provided to bias the rack 6 toward the left as viewed in Fig. 5.

Skip bar

The skipping mechanism is fully described in the Schaaff Patent No. 1,426,223 and comprises a skip bar 27 removably mounted on escapement rack 6 and is provided with a series of notches 28 and cam surfaces located at the fields where the carrier is to stop for the punching operation. The skip lifter is indicated by numeral 29. This skip lifter is provided with a hole 30 at its inner end adapted to engage a pin 31 and rest on a collar 32 secured to the pin. This pin 31 extends through a hole 33 in a toggle link 34 and into a pivoted T-bar 35. The pin is riveted in the T-bar. A pin 36 extends through a hole 37 in the other end of the toggle link 34. The pin 36 is first inserted in the upper bearing of a leaf spring 38, then through the toggle link and then into the lower bearing of said leaf spring. This leaf spring 38 is secured to the frame of the machine by means of a screw 39. The T-lever is provided with a slot 40 which engages over a pin 41. The leaf spring pressing on the toggle link tends to buckle the toggle one way or the other and the stop pin 41 engages one wall of the slot 40 or the other and limits the movement of the toggle lever. It will readily be seen that the skip lifter 29 will therefore be held in its retracted position where it is inoperative to in any way affect the regular escapement feed of the carriage, or held in its extended position where it becomes effective to modify the action of the escapement. The end of the skip lifter is held on the pin 31 by a plate 43.

Skip bars 27 are usually manufactured with a notch in the first column position. This notch is indicated by numeral 45 and comprises a cam edge, and a straight edge parallel to the longitudinal edges of the skip bar 27. It is desirable at times that punching be permitted in this first card column and at other times that the carriage be automatically skipped beyond this position and to the column position determined by the first notch 28.

Coming now to the present invention, the escapement bar 6 has preferably attached thereto by rivets 46 a bar 47 adapted when the carriage is moved by handle 2 to the first card column position to strike a shoulder 48 of a lever 49 pivoted at 50. The lower arm of lever 49 is provided with a

curved finger 51 engaging a circular extension of the T-bar 35. Rocking of the lever 49 will operate the toggle mechanism to shift the skip lifter 29.

The skip bar 27 is latched in position by means of a spring plate 52 more fully described in the Patent No. 1,772,186, it being noted that in the present machine this spring 52 is bent over to form a guide 53 beneath which fits a bar 54. The bar 54 at its right end is formed complementary with the notch 45. At its left end the bar 54 has a bayonet connection 55 with an arm 56 pivoted at 57 to the card carriage. As the escapement rack 6, skip bar 27, extension bar 54 are all carried by the carriage when the bar 54 is in the position shown in Fig. 7 the upper straight edge of the skip bar 27 is continued by a straight edge of the bar 54 to thus fill the notch 45. The lower cam surface 29a (Fig. 7), of the skip lifter coacts with the upper straight edge of the bar 54 and by reason of the fact that the end of the lifter 29 lies under the stepping dog 24, (see Fig. 5) it will elevate the dog 24 to release the escapement rack 6 and the card carriage for movement. Thereupon the lifter arm 29 coacts with the next notch 28 in the bar 27 and dog 24 will interrupt further movement beyond such point.

Upon a subsequent depression of a numeral key by means more fully described in the patent to Schaaff 1,426,223 a member 58 is operated when any numeral punch key is depressed and by rocking the T-lever 35 counterclockwise it will be automatically retracted. In the present construction such member may constitute an arm 58 secured to the rock shaft 19, the end thereof being in the path of an extension 59 of the T-lever 35.

Summarizing, when the carriage is returned by handle 2 to the first card column position the movement of the carriage itself will automatically cause the skip lifter to be shifted and the carriage automatically escaped to the first column of the next card field. The skip lifter is then automatically retracted when the first numeral punch key is operated.

When it is desired to punch in the first card column the carriage is returned by manual means other than the handle 2. The arm 56 is formed with a finger piece 60 and obviously since it is mounted on the carriage it constitutes a manual means for shifting the carriage to the right, similar to the handle indicated by numeral 174 of the Patent No. 1,772,186.

When arm 56 is rocked, obviously the extension bar 54 is shifted to the left to align the skip lifter with the notch 45 in the first card column position of the carriage. When arm 56 is rocked a lug 61 thereof strikes a bracket plate 62 secured to the carriage preventing further manual movement of the finger piece 60 so that continued pressure on the same will cause the carriage to be shifted to the right.

The bar 47 will, as before, shift the skip lifter 29 but the same will merely project through the notch 45 without elevating the stepping dog 24 to release the card carriage. Upon depression of a numeral key for punching in the first card column the carriage will be shifted a step and the skip lifter 29 will be retracted, as previously stated.

It is also desirable to permit the return of the carriage by finger piece 60 and still cause the holding of the carriage in the first column position without requiring initial adjustment of arm

56. To this end there is pivoted on the screw 57 a plate 63 provided with a finger piece 64 and a shoulder 65 normally abutting the lug 61. Finger piece 64 is first shifted to the right (Fig. 4) so that the shoulder 65 will rock the manual 56—60 to align the skip lifter 29 with the notch 45. The finger piece 64 can then be locked in a notch 66 of a bracket plate 67 attached to the bracket 62 by a screw 68.

10 While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following 15 claims.

What is claimed is as follows:

1. In a machine of the class described, in combination, a card carriage, an automatically operated mechanism for causing the carriage to be skipped from one field to another, means for returning the carriage to an initial operating position and for rendering the skipping mechanism operative, separately operated means for returning the carriage to the initial position and for rendering said skipping mechanism inoperative, and means for causing the automatic operation of said skipping mechanism, when said carriage is returned to the initial operating position by either of said means.

2. In a machine of the class described, in combination, a card carriage, a pair of separately operated means for moving said carriage to an initial operating position, means for causing said carriage to be automatically skipped to a predetermined position from its initial operating position, and means whereby the moving of said carriage by one of said separately operated means causes an effective operation of the carriage skipping means, and the moving of said carriage by the other means causes the skipping means to be ineffective in its operation.

3. In a machine of the class described, in combination, a card carriage, an automatically operated mechanism for causing the carriage to be skipped from one field to another, means for returning the carriage to an initial operating position and for rendering the skipping mechanism operative, separately operated means for returning the carriage to the initial position and effective by an initial adjustment of one of the separately operated means to render the skipping mechanism inoperative, and means for causing the separately operated means to be held in its initial position of adjustment, whereby said carriage is automatically retained in the initial position after its return without requiring the initial adjustment.

4. In a machine of the class described, a carriage carrying a card adapted to be operated upon, means for returning said carriage to an initial position and means for causing said carriage to be skipped automatically from the initial position to another position, and separately operated means for returning said carriage to said initial position and for preventing the effective action of said skipping means whereby the card is retained in its initial position for an operation thereon.

5. In a machine of the class described, in combination, a card carriage, an automatically oper-

ated carriage skipping mechanism for releasing the carriage for movement from one position to another, manual means operable to cause the movement of the carriage to an initial position, and means rendered operable by said manual 5 means for causing the operation of said skipping mechanism to be rendered ineffective to release the carriage for movement from its initial position.

6. In a machine of the class described, in combination, a carriage carrying a card, means operable for causing said carriage to be automatically skipped from initial operating position to a predetermined position of said carriage, means adapted to move the carriage to the initial operating position for causing said skipping means to be ineffective in its operation, and means for thereafter shifting said carriage step-by-step from the initial operating position for operation on the card in successive columns. 10 15 20

7. In a machine of the class described, in combination, a carriage carrying a card, means for shifting said carriage step-by-step from an initial operating position for operation on the card in successive columns, means adapted to be 25 operated each time said carriage is moved to an initial operating position for automatically skipping said carriage to a predetermined position, and means for moving said carriage to the initial operating position and for causing said 30 skipping means to be ineffective irrespective of its operation.

8. In a punching machine, in combination, a card carriage, means for holding said carriage at an initial operating position and causing it 35 to escape step by step from any position, means for preventing said means from holding the carriage and for causing the carriage to be skipped to a predetermined position, and means for moving said carriage and for causing the skipping 40 means to be inoperative whereby the first named means holds said carriage at the initial operating position.

9. In a machine of the class described, in combination, a carriage, manual means on said carriage for returning the latter to initial position, a carriage skipping mechanism, a carriage escapement mechanism operated by the latter to release the carriage and allow it to be skipped, and means for causing said manual means to 50 control the operation of the skipping mechanism.

10. In a machine of the class described, in combination, a card carriage, a skipping mechanism for causing the card carriage to be moved 55 from an initial operating position to another and including a skip lifter operable to render said skipping mechanism effective, means adapted to operate said skip lifter for each movement of the carriage to initial operating position, and 60 means effective when moving the carriage to initial operating position for rendering the skip lifter ineffective in its operation.

11. In a machine of the class described, in combination, a card carriage, an escapement mechanism for feeding said carriage step-by-step, a skipping mechanism including a skip lifter operable from a normal position each time the carriage is moved to an initial operating position 70 for causing said carriage to be shifted to another position, means for moving said carriage to initial position and having connections to render the skip lifter inoperable, and means operable coincidentally with the operation of said escapement 75

mechanism for thereafter shifting said skip lifter to its normal inoperable position.

12. In a machine of the class described, in combination, a card carriage movable for moving a card thereon column by column, a carriage skipping mechanism comprising a skip lifter and a skip bar having a notch in a predetermined position adapted to be received by said skip lifter, a carriage escapement mechanism, and a member movable to enter said notch upon a retracted position of said skip lifter, said member upon a movement of the skip lifter causing the release of said escapement mechanism and said carriage for a carriage skipping operation.
13. In a machine of the class described, a carriage escapement mechanism, a carriage skipping mechanism including a skip bar, a skip lifter received in a notch in said skip bar to prevent effective action of the escapement mechanism to

release the carriage when said skip lifter is operated, and a bar movable into said notch whereby said skip lifter upon its operation causes effective action of the escapement mechanism to release the carriage.

14. In a machine of the class described, a carriage carrying a card, means operated by a setting from normal for causing said carriage to be skipped automatically from an initial operating position to another, means for returning said carriage and for operating said skipping means, means for preventing the effective action of said skipping means irrespective of its setting from normal to allow an operation of the card in its initial position, and means operable when the card is operated on for setting said skipping means back to normal.

CHARLES O. WELLMAN.
